UNITED STATES PATENT OFFICE.

ANTHONY U. POTTER AND FRANK R. DANE, OF TAMPA, FLORIDA.

DESIGN FOR A SPOON.

SPECIFICATION forming part of Design No. 25,346, dated April 7, 1896.

Application filed February 27, 1896. Serial No. 581,073. Term of patent 7 years.

To all whom it may concern:

Be it known that we, ANTHONY U. POTTER and FRANK R. DANE, citizens of the United States, residing at Tampa, Hillsborough county, Florida, have invented and produced an original Design for Spoons, of which the following is a full, clear, and exact description, reference being had to the accompanying drawing, which represents a spoon bearing upon its bowl the figure of an orange in section.

The novel feature of our design is the bowl of a spoon of oval shape having within it an ornamentation representing an orange in section, which thereby presents a unique appearance.

In the drawing, *a* represents the handle, and *b* the bowl, of a spoon of oval shape.

Within the bowl *b* is an indelible illustra-

tion of an orange in section, in which *c* represents the rind or outer covering, *d* the diaphragms dividing the fruit into cells *e*, which contain the pulp *h* and seeds *i*. It is our intention to represent upon the manufactured article the aforesaid constituents in fast colors similar to those of the corresponding portions of the natural orange fruit, preferably enameeling the inner surface of the bowl.

We claim—

The design for a spoon substantially as shown and described.

Witness our hands this 24th day of February, 1896.

ANTHONY U. POTTER.
FRANK R. DANE.

In presence of—

N. W. STEARNS,
A. F. STEARNS.
